This invention relates to oscillators and more particularly to frequency stabilization of oscillators.

The class of oscillator to which the invention pertains includes either a mechanical vibratory system or a resonant circuit to which energy is continuously supplied to maintain continuous oscillations of constant frequency. Usually a small amount of energy is abstracted from the vibratory system, amplified and employed to provide a source for output oscillations and a source of driving energy for maintaining the vibratory system or circuit in oscillation.

The frequency stability of an oscillator of this character, which is the most important characteristic for most applications, is affected by many factors, including the physical conditions in and around the vibratory element and variations in the gain of the amplifier if the driving power and the loading of the vibratory element are affected thereby. Even in the case of a balanced tuning fork or crystal which is compensated for temperature variations or maintained at a constant temperature, the frequency of the oscillator is affected to an undesirable degree by changes in the loading of the vibratory element caused by unavoidable changes in the electrical characteristics of the associated amplifier. These changes are the result of changes in the supply voltages to the cathodes and electrodes of the amplifier, changes in the resistance or impedance of the amplifier circuits and other changes due to ageing and the like. The effect of these changes cannot be reduced to the desired extent unless unduly complicated regulating and other auxiliary equipment are provided. The size and cost of this auxiliary equipment in many cases precludes its use even though improved stability and related characteristics of the oscillator are desired. Furthermore the complexity of such control equipment introduces problems of construction and maintenance.

It has been generally recognized that minor changes in the loading of the vibratory system or resonant circuit will affect the frequency of the oscillator, i. e. the frequency of the element or resonant circuit which is utilized to control the frequency of the current in the output circuit of the oscillator.

It has also been noted that variations in the

2

characteristics of the amplifier referred to above will change the loading or damping sufficiently to cause a considerable change in the oscillator frequency. In the case of an oscillator having

5 a mechanical vibratory element, the amplitude of vibration of said element will vary if the driving energy is altered and it has been proposed to reduce the frequency variations of the oscillator resulting therefrom by controlling the gain 10 of the amplifier to maintain it substantially constant. For example, compensating arrangements have been proposed for varying the driving energy supplied to the vibratory element or system in response to changes affecting the normal oscillator frequency. However all of these methods 15 of compensation operate in response to a change in the frequency or amplitude and thus only approach in some degree the requirement of exact frequency stabilization.

20 It is the object of the present invention to provide an improved method and means of stabilizing the frequency of an oscillator by preventing changes in the loading of the resonant system or frequency-determining element due to

25 changes in the amplifier, and by limiting the feedback power so that changes in the amplitude of vibrations or oscillations of such element are small and do not affect the natural period. Stated in another way, the object of the invention

30 is to provide a non-dissipative coupling between the resonant system or element and the feedback amplifier so that the system or element is not damped by the feedback circuit. In addition such an arrangement has sufficient overall

35 gain to be dependably self-starting. It will be apparent that by controlling the damping factor and by maintaining the driving energy substantially constant, as by a limiter circuit, a constant frequency of oscillation of the frequency-determining system is attained in spite of minor

40 variations in either the amplitude of the vibration of the frequency-determining element or the characteristics of the associated amplifier.

Other objects and advantages of the invention 45 will appear from the following description of the preferred embodiments thereof, shown on the accompanying drawings, wherein

Fig. 1 shows a preferred embodiment of the invention, including a tuning fork for determining the frequency of the oscillator;

Fig. 2 shows a modification of the frequency-determining element of Fig. 1; and

Fig. 3 shows another embodiment of the invention employing a different coupling between the resonator and amplifier.

Referring to Fig. 1, there is shown a tuning fork 10; provided with inductive pick-up and drive coils 11 and 12, respectively, adjacent the tuning fork. As is well known in the art, the vibrations of the tines of the fork induce a small alternating voltage in the pick-up coil 11, which may be amplified and impressed upon the drive coil 12 to maintain the tuning fork in vibration. The mounting and construction of the mechanical vibratory element may be similar to that shown in the patent to A. G. Cooley, No. 2,174,414 and the fork per se may be sealed in an evacuated container to reduce the effect of air damping on the tines of the fork. For the higher frequencies, other types of mechanical vibratory elements, such as a piezo-electric crystal, may be employed, the tuning fork of the usual alloy steel composition being most suitable up to frequencies of the order of three thousand or four thousand cycles per second. As will be explained in connection with Fig. 2, a resonant circuit or network also may be employed to determine the frequency of the oscillator.

In the embodiment shown in Fig. 1, the alternating voltage derived from the pick-up coil 11 is impressed upon the control grid 15 of a space-discharge device 16 through the conductor 17. As shown, the space-discharge device 16 is a double triode having a cathode 18 and an anode 19 associated with the control-grid element 15; and a second section consisting of control-grid 21, cathode 22 and an anode 23 connected as an amplifier to supply energy to the drive coil 12 of the mechanical vibratory element.

It has been found heretofore that the use of a stable amplifier arranged to furnish a substantially constant driving energy to a tuning fork or equivalent element provides a relatively stable oscillator, if the fork is properly aged and insulated against substantial variations of temperature and ambient pressure. It is also known that changes in frequency resulting from shaking or changing the position of the fork may be minimized by using a small, compact tuning fork with the tines carefully matched as to size and mass. However, it has been found that even after taking all of these precautions, the frequency of the oscillator varies appreciably, say one or two parts or more per hundred thousand, if the characteristics of the amplifier change to a slight extent that is impossible to avoid. Such minor changes may result, for example, from variations in the components of the amplifier due to humidity variations, ageing and so forth, and particularly from variations in the damping of the fork or other frequency-determining element. Heretofore as pointed out above, it has been proposed to maintain the output of the amplifier or the driving energy supplied to the fork substantially constant, on the theory that if the driving energy were augmented, the amplitude of vibration of the fork would increase and this would result in greater damping of the fork itself, with decreased period of vibration. It is obvious that increased amplitude results from increased driving energy but it has not been recognized that the damping effect is primarily the result of the coupling heretofore employed between the pick-up coil of the fork and the amplifier. I have found that by increasing the impedance of the

input circuit to the amplifier substantially to infinity, the stability of the oscillator is markedly increased even if the driving energy and amplitude of vibration of the fork are permitted to vary somewhat. The improvement may be realized by input impedances which are relatively high, compared to the impedance of the inductive pick-up coil measured at the frequency of the oscillator, provided the phase relation between the potentials at the terminals of the drive element 12 and the input electrode 15 of the amplifier is held constant. If the input impedance of the amplifier is of the order of one megohm, excellent results are obtained with respect to increased frequency stability. Obviously the higher the input impedance, the less the damping of the fork.

One method of accomplishing this result which has been found to work well in actual practice is to employ an isolating stage having substantially infinite input impedance, as by connecting the pick-up coil directly to the control grid 15 of the space-discharge device connected to the amplifier; and an un bypassed cathode-bias resistor 25 is connected to the cathode 18 of the space-discharge device. With this arrangement in a tube of the 6F8 or 7N7 type, for example, the input impedance of the tube composed essentially of the inter-electrode capacities is of the order of several megohms at a frequency of one or two thousand cycles. Many other types of tubes are also suitable for this application, of course. Under these conditions, no grid current flows in the control-grid circuit under operating conditions and the damping effect of the amplifier upon the tuning fork is exceedingly small, practically zero, even if the voltage across the terminals of the pick-up coil increases as a result of increased amplitude of the fork. It is to be noted that the gain in the first or isolating stage of the amplifier is negligible under these conditions, the purpose of the first stage represented by the electrodes 15, 18 and 19 being merely to provide a non-dissipative coupling between the fork and the subsequent stage or stages of the amplifier so that the alternating voltage of the pick-up coil 11 is coupled to the amplifier without the possibility of a change in the damping effect or absorption of energy from the fork element, if the sources of cathode heater and space current of the amplifier vary.

As shown, the output of the first stage of the amplifier is coupled through the coupling condenser 26 to the control-grid electrode of an amplifier 27, which is shown as a high gain pentode tube. The tube 27 is arranged to act as a limiter by adjusting the circuit constants so that the signal impressed thereon causes grid saturation. The constant-level output of the tube 27 is impressed upon the control grid 21 of the second section of the tube 16 through a coupling condenser 28 and resistor 29. The amplified constant-level output current of said section is impressed upon the drive coil 12 of the fork element 65 through the coupling condenser 31.

With this arrangement it is found that substantially perfect stabilization of the fork frequency is obtained even if the characteristics of the amplifier vary to such a degree that the frequency of the oscillator as constructed heretofore would be affected adversely. The amplifier is particularly sensitive to changes in cathode heater current, and in actual practice it is found that such variations that would cause a change 75 in oscillator frequency of one or two parts or

more per one hundred thousand in the prior oscillators under favorable conditions, may cause a change of only approximately one part per million as a result of the improved coupling between the pick-up coil of the fork element and the amplifier.

In order to provide a constant-level output current of constant frequency from the oscillator, a connection is made from the output circuit of the limiter tube 27 through a resistor 32 to an auxiliary amplifier 33. As shown the tube 33 is of the double triode type having its input circuits connected in parallel, thus providing two output circuits 34 for supplying two separate load circuits. The voltage divider including resistor 35 connected in series relation with one of the input circuits of the tube 33 reduces the amplitude of the current in the associated output circuit. The additional amplifier 33 prevents a varying load circuit from affecting the frequency stabilization of the oscillator but other modifications of the output circuit will occur to those skilled in the art and may be used if desired.

Fig. 2 illustrates a resonant circuit or phase-shifting network, which may be substituted for the fork element shown in Fig. 1 by connecting the same to the terminals 13. The phase-shifting network of Fig. 2 of conventional design comprises a plurality of series condensers 31, 38 and 39 having shunt resistors 41, 42 and 43 connected as shown to effect a 180-degree phase shift between the input and output voltages at the desired oscillator frequency. The resistor 41 may be adjustable in order to permit the oscillator frequency to be adjusted to the desired value. Heretofore the use of a resonant circuit has been considered impractical in an oscillator where a high degree of stability is desired because of the effect upon the frequency of the oscillator produced by slight variations in the characteristics of the associated amplifier. However it is found that a high degree of stability is obtained in such an oscillator if the resonant circuit is coupled to the amplifier through a non-dissipative coupling as described.

Fig. 3 shows a modification in which the signal from the frequency-determining element or circuit 51 is impressed on the control electrode 52 of a space-discharge device 53. The device 53 is arranged in such manner that the potential of the cathode 54 varies directly with the potential applied to the control electrode, such as in a conventional cathode follower, in which the flow of D. C. grid current is obviated. Hence the input impedance is extremely high at low frequencies, being solely dependent upon electrode and circuit capacitances. The output from the cathode follower 53 is coupled through condenser 55 to the control electrode 56 of an amplifier 57 constituting a conventional limiter stage. The output of this stage, which as shown is identical with the limiter stage of Fig. 1, is coupled directly or through a coupling condenser to another cathode follower 58, which provides a low-impedance source of power to feed the frequency-determining element or resonant circuit 51 in order to obtain a high order of regulation. Thus the output of the cathode follower is independent of changes in the load imposed by the frequency-determining element or resonant circuit. A potentiometer 60 or other amplitude control device may be employed to adjust the feedback power to such a value as to produce satisfactory self-starting characteristics and optimum stability.

Conductor 61 may be connected to the circuit or device to be supplied by the oscillator.

At frequencies where the pick-up tube input impedance becomes a substantial shunt on the frequency-determining element or resonant circuit, load and phase shift may become large enough to be detrimental to frequency stability. In accordance with the invention, selection of the pick-up tube type and design of the frequency-determining element or resonant circuit to present a relatively low impedance to the pick-up tube should be such as to minimize the damping effect of the coupling to the amplifier, as explained above.

While several preferred embodiments of the invention have been described in detail for the purpose of explaining the principles involved, various modifications in the circuit arrangement and components may be made without departing from the scope of the invention as defined in the appended claims.

I claim:

1. An oscillator comprising a frequency-determining system or element adapted to resonate at a predetermined frequency, means to supply energy to said system or element to maintain continuous oscillations thereof, said means including a multi-stage amplifier, the first stage of which embodies a space-discharge device having a cathode, an anode and a control electrode conductively connected in potential-transferring relation to the frequency-determining system or element, biasing means connected to the electrodes of said space-discharge device to maintain the control electrode at a negative potential with respect to the cathode and at a value sufficient to prevent the flow of current in the control electrode circuit under oscillating conditions to minimize changes in the loading on the frequency determining system or resonant circuit, and means for maintaining the driving energy supplied to said system or element substantially constant.

2. An oscillator comprising a frequency-determining system adapted to resonate at a predetermined frequency, pick-up and drive elements therefor and means to supply energy to the drive element of said system to maintain continuous oscillations thereof, said means including an electronic tube amplifier coupled to the pick-up and drive elements of said frequency-determining system, said means also including an isolating stage for said pick-up element consisting of a space-discharge device embodying a cathode, an anode and a control electrode, said control electrode being conductively connected to said pick-up element, and means including an unbypassed resistor connected in a common portion of the cathode-anode and cathode-control electrode circuits of said discharge device for maintaining said control electrode at a negative potential with respect to said cathode and of a value sufficient to prevent the flow of direct current in the control electrode circuit under oscillating conditions.

3. An oscillator comprising a frequency-determining system having a natural period of vibration or oscillation, a pick-up element therefor, a feedback circuit arranged to supply energy to said system to maintain continuous oscillations thereof and a non-dissipative coupling between the pick-up element and said feedback circuit having an impedance of the order of a megohm or more at the oscillator frequency, said coupling consisting of a space-discharge device embodying a cathode, an anode and a control electrode, said

control electrode being conductively connected to said pick-up element, and biasing means for maintaining said control electrode negative with respect to said cathode including an unbypassed resistor connected in the cathode lead of said space-discharge device for preventing the flow of direct current in the control electrode circuit under oscillating conditions.
